UNITED STATES PATENT OFFICE.

HENRY J. ENNIS, OF WASHINGTON, DISTRICT OF COLUMBIA, ASSIGNOR
TO FRANK H. FINLEY AND ROBERT CALLAHAN, BOTH OF SAME
PLACE, AND HARRY GRANGER, OF ROCHESTER, AND HUNT M. BUT-
LER, OF NEW YORK, N. Y.

AUTOMATIC VENDING APPARATUS.

SPECIFICATION forming part of Letters Patent No. 365,912, dated July 5, 1887.

Application filed March 14, 1887. Serial No. 230,926. (No model.)

To all whom it may concern:

Be it known that I, HENRY J. ENNIS, a citizen of the United States, residing at Washington city, in the District of Columbia, have invented certain new and useful Improvements in Automatic Cigarette-Vending Apparatus; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 This invention relates to certain improvements in that class of apparatus for distributing and delivering cigarettes for sale, in which is provided a series of devices so arranged relatively in a casing containing the cigarettes 20 that by depositing a coin through a suitable aperture at the top of the casing the weight will operate certain trip mechanism to release or drop one cigarette into a drawer below, and the drawer be unlocked, so that it can be 25 drawn out and the cigarette removed, while the coin will be deposited in a safe receptacle.

The invention consists in certain details of construction, hereinafter specified, and pointed out in the claims.

30 The objects of my invention are attained by the means illustrated in the accompanying drawings, in which—

Figure 1 represents a perspective view of my improved apparatus. Fig. 2 is a side elevation with the side removed to show the 35 operating mechanism. Fig. 3 is a central longitudinal section. Fig. 4, a section on line *x x*, Fig. 3; and Fig. 5 is a horizontal section on the line *y y* of Fig. 3.

40 Referring to the drawings, the letter *A* indicates a cabinet or casing of any suitable material and of any ornamental form, which contains the cigarette-receptacle *B*, which is a segmental chamber constructed of sheet metal, 45 having a closed side, *C*, and an open side opposite thereto, through which the cigarettes are inserted. At the lower end of the receptacle *D* is a vertical chamber, *E*, into which

the cigarettes fall, and from which they are discharged one at a time into a drawer, *G*, 50 which has a space arranged to contain a single cigarette alone. The space is open at the bottom, so as to drop a cigarette out onto a shelf, *H*, as required.

The front of the cigarette-receptacle is provided with a hinged shelf, *I*, which is automatically raised and lowered by a rocking lever, *K*, when the drawer is drawn out to permit a fresh cigarette from the receptacle to take the place of the one dropped out below. 55 This lever, through the medium of a spring, *K'*, holds the shelf down normally, and is caused to raise it by means of an adjustable set-screw, *L*, passing through a stud, *L'*, secured to drawer. The drawer is provided 60 with a slot, *M*, through which passes a stop, *N*, which limits its movement.

The letter *P* indicates a curved guide or chute, the upper part of which is curved and the lower part vertical. The said guide or chute has grooved ways at its sides, which guide the coin from the deposit-aperture to the lower end of the chute. Near said lower end is a weighted trip-lever, *R*, attached to the chute, which normally engages a notched 70 bar, *S*, secured to a stud rising from one side of the drawer, so as to lock the drawer when closed. The lever is provided with an arm, *T*, against which the coin strikes when dropped, and swings the lever free from the notched 75 bar, so as to unlock the drawer and permit it to be drawn out and allow the coin to be deposited in a receptacle, *U*.

The casing at each side is provided with hinged doors *V V'*, which open outward. The 80 door *V* is provided with a lock, *W*, of ordinary description, and the door *V'* with a staple, *X*, which is engaged by an angle-lever, *Y*, when pressed back by the spring-rod *Z*, which is operated by the door *V* when the same is closed 85 and locked, so as to lock the whole case simultaneously.

Having thus described my invention, what I claim, and desire to secure by Letters Patent, is—

90 1. The combination, in a cigarette-delivery

apparatus, of the curved chute, the weighted trip-lever, the notched bar engaged thereby, the sliding drawer, the receptacle, the hinged shelf, and the rocking lever connected thereto, substantially as described.

2. The combination, in a cigarette delivering apparatus, of the sliding drawer, the mechanism for operating the same to lock and unlock it, the rocking lever, and the retracting spring for operating the shelf, and the adjustable set-screw.

3. The combination of the casing, the locking devices, mechanism for feeding the articles into the drawer, the said drawer, and adjustable means on the drawer for operating the feeding mechanism, substantially as described. 15

In testimony whereof I affix my signature in presence of two witnesses.

HENRY J. ENNIS.
